CLAIM

The ornamental design for an automobile, as shown and described.

DESCRIPTION

FIG. 1 is a front view of an automobile showing my new design.

FIG. 2 a rear view thereof.

FIG. 3 a top plan thereof.

FIG. 4 a right side view thereof the left side being a mirror image of the right side.

FIG. 5 a front perspective view thereof; and,

FIG. 6 a rear perspective view thereof.

The bottom view is omitted because it is devoid of any surface ornamentation.
